UNITED STATES PATENT OFFICE.

ERASTUS E. WINKLEY, OF LYNN, MASSACHUSETTS.

CARBURETER.

1,240,281.

Specification of Letters Patent. Patented Sept. 18, 1917.

Application filed February 26, 1912. Serial No. 679,853.

To all whom it may concern:

Be it known that I, ERASTUS E. WINKLEY, a citizen of the United States, residing at Lynn, in the county of Essex and State of 5 Massachusetts, have invented certain new and useful Improvements in Carbureters; and I do hereby declare the following to be a full, clear, and exact description of the invention such as will enable others skilled 10 in the art to which it appertains to make and use the same.

The present invention relates to carbureters, and more particularly to that class of devices which are employed for the carbureting or vaporizing of hydro-carbons or 15 other liquid fuels for use in connection with internal combustion motors.

Internal combustion motors as at present constructed are commonly set in operation 20 by giving a few rotations to the crank shaft either by hand or by means of some auxiliary starting device, during which rotations an explosive mixture is drawn from the carbureter into the cylinders of the motor 25 where it is ignited, starting the motor in its regular operation. Considerable difficulty has been experienced, particularly in cold weather and with the lower grades of fuel and the larger sizes of motor in vaporizing a sufficient amount of the liquid fuel 30 in these preliminary rotations of the crank shaft to form a mixture rich enough to be ignited. The principal object of the present invention is to provide a carbureter, 35 which is particularly designed to facilitate the starting of the motor by insuring the supply of combustible or explosive mixture at low temperatures and with the less volatile grades of fuel and practically irrespec- 40 tive of the speed of rotation imparted to the crank shaft.

With this and other objects in view hereinafter to be referred to, the present invention consists of the devices and combinations 45 of devices hereinafter described and more particularly defined in the claims.

Figure 1 is a front elevation of my improved carbureter;

Fig. 2 is a bottom plan view of the same; 50 Fig. 3 is a vertical section on line 3—3, Fig. 2, looking in the direction of the arrows; and

Fig. 4 is a vertical section on lines 4—4, looking in the direction of the arrows.

55 In the specific form of carbureter illustrated in the drawings, 11 is the chamber

located in the lower portion of the carbureter and provided with the fuel nozzle 12 having the annular orifice 13. Fuel is supplied to the nozzle through the passages 14 60 from a float chamber 15 in which the fuel is maintained at a substantially uniform height by means of a hollow float 16 and fuel valve 17 which controls the admission of fuel from the supply pipe 18. The escape of fuel 65 through the annular orifice 13 is regulated by means of the needle valve 19, the shank of which projects through the bottom of the carbureter at 21 and is provided with the lock nut 22 to hold the valve in its adjusted 70 position.

Air is supplied to the carbureter through the air intake pipe 24 provided with the holes or ports 25, the passage from the intake pipe to the carbureter being normally 75 free and unobstructed. The bottom of the carbureter is provided with a depression adjacent the intake pipe for a purpose shortly to be made clear. An auxiliary supply of air is provided through the auxiliary air 80 port 26 controlled by the valve 27 fixedly secured upon the oscillating shaft 28 by means of the bracket 29. The shaft 28 is mounted in the bearings 31 and carries at its upper end rigidly secured thereto the 85 cam-shaped arm 32 which is engaged by one arm 33 on pivoted bell crank lever 34, the other arm 35 of which is pressed toward the left, as shown in Fig. 2, by means of the spring-pressed rod 36, one end of which 90 bears against the lever 35 while the other is free to slide within the thumb nut 37 which serves as an adjustable abutment for the spring 38, being adjustably mounted in the pivoted bracket 39. This mechanism 95 tends normally to hold the auxiliary air valve 27 closed but permits said valve to open whenever the suction or degree of vacuum within the carbureter reaches an amount sufficient to overcome the compression of spring 38.

The gaseous mixture is delivered from the carbureter through the outlet port 41 at the top of the carbureter, as viewed in Fig. 1, and adjacent said port is located the throttle 105 42 which is in the form of a butterfly valve rigid upon a valve spindle 43 and adapted to be actuated by means of the arm 44 secured to the spindle by the set screw 45. The arm 44 has projecting from it and at 110 right angles to one another the two shorter arms 46 and 47 carrying the stop screws 48

and 49 respectively, which are adapted to engage opposite sides of the abutment or lug 51 and limit the rotation of the valve spindle in both directions.

- 5 In order to facilitate the production of an explosive mixture the air intake pipe 24 has been provided with the air intake valve 52 mounted upon the rod 53 and adapted to be moved from the position shown in 10 broken heavy lines in Fig. 1 to the position shown in dotted outline in said figure and in full lines in Fig. 3. This valve is provided with an air passage or orifice 54 adjacent its bottom edge and with a deflector 55 15 to deflect the air passing through said orifice downwardly into the depressed bottom of the carbureter. The valve 52 and rod 53 are adapted to be actuated by the operator from any convenient point through the link 56 20 and other suitable connections.

In order to hold the auxiliary air valve 27 closed when the valve 52 is in the position illustrated in Fig. 3, the lower end of shaft 28 has been provided with the finger 57 25 rigidly secured thereon adapted to be engaged by the end of lever 58 pivoted upon stud 59 and connected at its lower end through the link 61, rod 62, and arm 63 with the valve rod 53 and actuating link 56 30 for the air intake valve 52. When the link 56 is moved to the left, as shown in Figs 1, 2 and 3, the free end of lever 58 is swung to the right as viewed in Fig. 2, closing the auxiliary air valve 27 if it should be open 35 and holding it closed so long as the valve 52 is in position shown in Fig. 3. When the connecting link 56 is moved in the opposite direction the valve 52 will be carried beyond the apertures 25 in the air intake pipe and 40 the auxiliary air valve 27 will be rendered free to open if the suction within the carbureter is sufficient.

In the normal operation of a motor the actuating link 56 will be retained in its extreme right-hand position, leaving the air intake pipe unobstructed and the auxiliary air valve free to open. The liquid fuel within the nozzle 11 will be drawn through the 50 annular orifice 13 and vaporized by the air passing through the carbureter, the amount of fuel delivered being regulated by the needle valve 19, and an excessive suction and an over supply being prevented by the auxiliary air valve 27.

55 When it is desired to start the motor in operation the link 56 will be moved toward the left, thereby throttling the supply of air through intake pipe 24, at the same time holding the auxiliary air valve closed. If, 60 now, the crank shaft of the motor be given a few preliminary rotations either by hand or by means of some auxiliary starting device, an abnormally high degree of suction or vacuum is produced within the carbureter, 65 causing the liquid fuel to escape freely

through the annular orifice 13. Whatever fuel is not immediately vaporized falls to the bottom of the carbureter and collects in the depression therein, where it is at once picked up and vaporized by the stream of 70 air which passes at high velocity through the orifice 54, and is directed downwardly against the fuel by means of the deflector 55. A gaseous mixture of sufficient richness to be easily ignited is thus produced even in 75 the coldest weather or with a low grade of fuel, and practically irrespective of the speed of rotation of the crank shaft.

As soon as the motor is started in operation the actuating link 56 may be moved to 80 the right either part way or to the limit of its movement, as circumstances may require. When it is desired to stop the motor temporarily, a rich explosive mixture may be left in the cylinders merely by moving the 85 connecting link 56 to the left just before the motor is stopped.

It is to be understood that my invention is not limited to any of the specific features of construction illustrated and described except where so expressly defined in the claims, but may be embodied in many other forms and arrangements.

Having thus described my invention, what I claim is:

1. A carbureter, having, in combination, a chamber provided with a depressed bottom to retain fuel and with an air inlet at one side of the chamber adjacent the depressed bottom, a valve normally held in fixed position and adjustable by the operator to a position to substantially close the air inlet, said valve being provided with an air passage adjacent the depressed bottom of the chamber and with a downwardly projecting lip adjacent the air passage to deflect the air downwardly into the depressed bottom, and means for supplying fuel to the chamber, substantially as described.

2. A carbureter, having, in combination, a chamber provided with a depressed bottom to retain fuel and with an air inlet at the side of the chamber adjacent the depressed bottom, an air intake pipe connected with the air inlet and provided with an air port in the side thereof, a piston valve mounted in said pipe and normally held in fixed position at one side of said air port to permit air to pass freely from said port through the air inlet, and movable to a position between 110 said air port and the air inlet, the valve being provided with an air passage adjacent the depressed bottom, means for adjusting the position of the valve, and means for supplying fuel to the chamber, substantially as 115 described.

3. A carbureter, having, in combination, a chamber provided with an air inlet at the side adjacent its bottom, an air intake pipe connected with the air inlet, said pipe being 120

provided with a lateral air port, a piston valve in the air pipe normally held in fixed position and movable by the operator from a point beyond the air port to a point beyond the air port and the chamber, an auxiliary air intake port, a spring-pressed auxiliary intake valve for closing the same, and connected mechanism under the control of the operator for positively closing and holding closed the auxiliary intake valve and for moving the piston valve to the position intermediate the air port and the chamber, substantially as described.

4. A carbureter, having, in combination, a chamber provided with a main air inlet, a main valve for closing said air inlet, an auxiliary air port, a pivoted auxiliary intake valve for closing the same, an arm

rigidly connected with the said valve, means under control of the operator for actuating the main valve, devices connected with said means, including a finger adapted to engage the arm connected with the auxiliary intake valve to positively close and hold closed said auxiliary valve when the main valve is adjusted by the operator to close the air inlet, and to be moved out of contact with said arm to render the auxiliary valve free to open when the main valve is adjusted by the operator to open the air inlet, and means for supplying fuel to the chamber, substantially as described.

ERASTUS E. WINKLEY.
